UNITED STATES PATENT OFFICE.

EDWARD S. SMITH, OF WATERBURY, CONNECTICUT.

DESIGN FOR A TOBACCO-PIPE MOUNTING.

SPECIFICATION forming part of Design No. 26,354, dated December 1, 1896.

Application filed October 29, 1896. Serial No. 610,512. Term of patent 7 years.

To all whom it may concern:

Be it known that I, EDWARD S. SMITH, a citizen of the United States, residing at Waterbury, in the county of New Haven and State 5 of Connecticut, have invented and produced a new and original Design for Tobacco-Pipe Mountings, of which the following is a specification.

My design is illustrated in the accompanying drawings, in which—

Figure 1 shows a perspective view of part of a tobacco-pipe provided with my ornamental mounting. Fig. 2 is a transverse section in the plane $x x$, Fig. 1.

15 In the drawings the letter A designates the bowl of a tobacco-pipe, and B is the hollow stem which extends from said bowl.

C is the ornamental mounting, which is provided with an inwardly-projecting flange 10 and the body of which is ornamented by bent 20 strips 11 11, scrolls 12 12, and leaves 13 13, said scrolls being formed to represent leaves or twigs of a plant.

What I claim as new, and desire to secure by Letters Patent, is—

25 The design for a tobacco-pipe mounting as shown and described.

In testimony whereof I have hereunto set my hand in the presence of two subscribing witnesses.

EDWARD S. SMITH.

Witnesses:

C. H. GARDNER,
JAS. H. MULLIGAN.
